Design No. 561.

James L. Jackson.

Crate frame No. 2.

Patented 3rd May 1939. —

Ms. 561

James L. Jackson, of New York, N.Y.
Letters Patent No. 561. Dated May 3^d 1853.

The schedule referred to in these Letters Patent and making part of the same.

To all whom it may concern:

Be it known that I, James L. Jackson, of the City
County, and State of New York, have invented or produced, a certain new and original de-

D

sign for a grate-frame, and I do hereby declare the following to be a full clear and exact description of the same reference being had to the accompanying drawing making apart there-of, and which represents one half of the frame complete - the other half which is precisely the same in configuration, being shown in outline only, and representing by a sectional line the projection of the mouldings, &c.

The inner margin of the frame has straight sides to the jambs, with a semi-circular top - the whole margined by a bead *a*, outside of which is a broad cavetto moulding *b*, terminating underneath the ornamental margin of the projecting portion of the frame.

On the jamb base *c*, is a volute *d*, curving inwards which is flanked with a highly wrought fruit piece *e*, pendant from the top of the volute. At the top of the volute its curve reverses, and widens out into a plain concavo-convex margin *f*, which sweeps around and forms the outer part of the frame.

From a point, near the top of the straight part of the jamb, starts out a vine *g*, which encloses in each of its scrolls a leaf *h*. The top centre piece is formed by the two vines entwining and terminating with a leaf *i*, and a trifoliate *j* above *i*, below to complete the design - the spaces between the ornaments being in open work.

The shaded line *x*, *x*, represents a section through the frame, showing the projection of the several parts thereof.

Having thus fully described the nature of my design, what I claim there is new and desire to secure by letters patent, is the combination and arrangement of the figures, flowers, and ornaments herein represented, the whole forming an ornamental design for a grate frame.
